US00D918272S

(12) **United States Design Patent** (10) Patent No.: **US D918,272 S**
(45) Date of Patent: ** May 4, 2021

(54) **ELECTRONICS HEAD**

(71) Applicant: **Wayne Fueling Systems LLC**, Austin, TX (US)

(72) Inventors: **John Joseph Morris**, Austin, TX (US); **Scott R. Negley, III**, Austin, TX (US); **Annika Birkler**, Austin, TX (US); **Sam Moon**, Austin, TX (US); **Randal S. Kretzler**, Austin, TX (US); **Brian Tholen**, Austin, TX (US); **Daniel Holmes**, Austin, TX (US); **Artemus A. Shelton**, Hutto, TX (US); **Henry Fieglein**, Leander, TX (US); **Paul Laiming**, Austin, TX (US); **Lucas Wade**, Austin, TX (US)

(73) Assignee: **Wayne Fueling Systems LLC**, Austin, TX (US)

(**) Term: **15 Years**

(21) Appl. No.: **29/751,756**

(22) Filed: **Sep. 23, 2020**

CLAIM

The ornamental design for an electronics head, as shown and described.

DESCRIPTION

FIG. 1 is a perspective view of a new design of an electronics head shown on a fuel dispenser; FIG. 2 is front view of the electronics head of FIG. 1, the back view being a mirror image thereof; FIG. 3 is a left view of the electronics head of FIG. 1; FIG. 4 is a right view of the electronics head of FIG. 1; FIG. 5 is a top view of the electronics head of FIG. 1; and, FIG. 6 is a bottom view of the electronics head of FIG. 1. The broken lines in the drawings form no part of the claimed design.

1 Claim, 4 Drawing Sheets
